UNITED STATES PATENT OFFICE.

WALTER R. KAHNS AND KARL KELLER, OF BROOKLYN, NEW YORK, ASSIGNORS TO
J. H. WHITE MANUFACTURING COMPANY, OF BROOKLYN, NEW YORK, A CORPORA-
TION OF NEW YORK.

LIGHTING FIXTURE.

Application filed May 20, 1926. Serial No. 110,349.

Our invention relates to lighting fixtures, and especially to electroliers and chandeliers in which a plurality of arms supporting lighting devices project from a common support, and the object of the invention is to effectively prevent relative displacement of such arms.

In the accompanying drawing:—

Figure 1 is an elevation in reduced size of a hanging lighting fixture to which our invention is applicable.

Fig. 2 is a central vertical section in larger size partly broken away.

Fig. 3 is a top view of the upper ends of the lamp supporting arms as connected to their support, the coupling member and nipple being removed, and

Fig. 4 is a cross section on the broken line 4—4 of Fig. 2.

Referring to the drawing, 10 indicates a section of pipe having a plurality of spaced threaded projections 11 on the same horizontal line secured to the pipe by solder or in any suitable manner. The lamp supporting arms 12 are preferably hollow or tubular, and also preferably hexagonal with two opposite sides depressed inwardly towards each other longitudinally.

These arms at their upper portions lie vertically and side by side against the pipe 10, the depressions on their innermost sides conforming to the outer surface of the pipe while the depressions on their outermost sides add to the ornamental appearance.

Each of these arms is provided with an opening 13 through which the threaded projections 11 on the pipe 10 pass, and a knob 14 is screwed upon the projecting end of each of the threaded members 11 thereby removably securing the arms 12 to the pipe 10 at this point. At a predetermined distance below such connection the arms are curved outwardly and upwardly, there being ornamental shells 15 attached to their ends in which the electric lamps 16 are seated. These lamps may be of the candle type as shown, or of any other suitable character.

The upper ends of the arms 12 are flush with the upper end of the pipe 10 and a cap 17 is placed over the top of the pipe, the cap being provided with a central opening 18 of a diameter corresponding with the opening in the pipe which is interiorly threaded at the upper end. The outer edge of the cap 17 is provided with spaced downwardly turned

lugs or projections 19, one of which passes into the open upper end of each arm 12.

A coupling member 20 is provided having a stem 21 exteriorly threaded which is screwed into the upper end of the pipe 10 and bears upon the top surface of the cap whereby the upper ends of the arms 12 are securely held to the pipe.

The body of the member 20 has an opening 22 through its center for the passage of the conductor wires (not shown), above which it terminates in a ring 23 which is interiorly threaded. A hollow exteriorly threaded nipple 24 is screwed into the threaded ring 23, and upon its upper end receives the threaded hub 25 of a hook or ornamental bail 26 to which the chain 27 for suspending the fixture is connected. An ornamental shell 28 covers the upper ends of the arms 12 and pipe 10 and lower part of the member 20, while another shell 29 covers the upper part of the member 20 and the nipple 24. An ornamental knob or plug 30 is fixed to the lower end of the pipe 10.

While we have described the member 10 as a section of pipe, it is obvious that this member may be a solid rod having a threaded recess in its upper end to receive the threaded stem 21 of the coupling member 20, without departing from the nature and spirit of our invention.

Our invention provides a lighting fixture of the character described in which the lamp supporting arms are effectively prevented from relative angular displacement when in use, and of very ornamental appearance.

We claim as our invention:

1. In a lighting fixture, a section of pipe, a plurality of tubular lamp supporting arms surrounding said pipe with their upper ends flush with the top of said pipe, said arms bearing against the outer surface of the pipe a portion of their length, means for detachably connecting the upper ends of the arms to the pipe, and means for detachably connecting said arms to the pipe at a predetermined distance below their upper ends.

2. In a lighting fixture, a section of pipe, a plurality of tubular lamp supporting arms surrounding said pipe with their upper ends flush with the top of said pipe, said arms bearing against the outer surface of the pipe a portion of their length, a cap with a central opening seated upon the top of said pipe and provided with spaced downwardly turned

- turned fingers on its outer edge, which fingers enter the upper open ends of the respective arms, and means for detachably connecting said arms to the pipe at a predetermined distance below their upper ends.
3. In a lighting fixture, a section of pipe, a plurality of tubular lamp supporting arms bearing against said pipe a portion of their length, the upper ends of said arms being flush with the top of the pipe, a cap with a central opening seated upon the top of said pipe and provided with spaced downwardly turned fingers on its outer edge, which fingers enter the upper open ends of the respective arms, means for locking said cap in position, and means for detachably connecting said arms to the pipe at a predetermined distance below their upper ends.
4. In a lighting fixture, a section of pipe, a plurality of tubular lamp supporting arms bearing against said pipe a portion of their length, the upper ends of said arms being flush with the top of the pipe, a cap with a central opening seated upon the top of said pipe and provided with spaced downwardly turned fingers on its outer edge, which fingers enter the upper open ends of the respective arms, a coupling member provided with a threaded stem screwed into the upper end of the pipe and bearing upon the top of said cap, and means for detachably connecting said arms to the pipe at a predetermined distance below their upper ends.
5. In a lighting fixture, a section of pipe, a plurality of tubular lamp supporting arms bearing against said pipe a portion of their length, the upper ends of said arms being flush with the top of the pipe, a cap with a central opening seated upon the top of said pipe and provided with spaced downwardly turned fingers on its outer edge, which fingers enter the upper open ends of the respective arms, a coupling member having a central opening through its body and provided with a threaded stem screwed into the upper end of said pipe and bearing upon the top of said cap, said coupling member above said opening being interiorly threaded, an exteriorly threaded nipple screwed therein, means for detachably connecting said arms to the pipe at a predetermined distance below their upper ends, and ornamental shells covering the upper ends of said arms and pipe and said coupling member and nipple.
6. In a lighting fixture, a section of pipe, a plurality of tubular lamp supporting arms bearing against said pipe a portion of their length, the upper ends of said arms being flush with the top of the pipe, a cap with a central opening seated upon the top of the pipe and provided with spaced downwardly turned fingers projecting into the upper open ends of the respective arms.
7. In a lighting fixture, a section of pipe, a plurality of tubular lamp supporting arms surrounding said pipe, a cap with a central opening seated upon the top of the pipe and provided with spaced downwardly turned fingers projecting into the upper open ends of the respective arms.
8. In a lighting fixture, a section of pipe, a plurality of tubular lamp supporting arms surrounding said pipe, a cap with a central opening seated upon the top of the pipe and provided with spaced downwardly turned fingers projecting into the upper open ends of the respective arms, and means for detachably connecting said arms to the pipe at a predetermined distance below their upper ends.
9. In a lighting fixture, a central vertical support provided with a plurality of spaced threaded projections at or about the middle of its length, a plurality of arms surrounding said support each having an opening through which the respective projections on the support extend, a knob screwed upon the end of each projection exterior of the arms, means for detachably connecting the upper ends of said arms to the support, means for detachably connecting the arms to the central support at a predetermined distance below their upper ends, a coupling member connected to the upper end of the central support, said coupling member having a central opening through its body, above which opening it is interiorly threaded, and an exteriorly threaded nipple screwed therein.
6. In a lighting fixture, a section of pipe, a plurality of tubular lamp supporting arms bearing against said pipe a portion of their length, the upper ends of said arms being flush with the top of the pipe, a cap with

Signed by us this 11 day of May, 1926.
